CLAIM

The ornamental design for a spatial digital timepiece face, as shown and described.

DESCRIPTION

FIG. 1 is a front view of a spatial digital timepiece face of the present invention, indicating a representative time of 12:00;

FIG. 2 is a front view of the spatial digital timepiece face of the present invention, indicating a representative time of 12:15;

FIG. 3 is a front view of the spatial digital timepiece face of the present invention, indicating a representative time of 3:42; and,

FIG. 4 is a front view of the spatial digital timepiece face of the present invention, indicating a representative time of 11:10.

The side elevational views, top and bottom plan views, and rear elevational view is not visible during normal use and forms no part of the claimed design.
